DELINQUENCY CARD SELECTING MACHINE

Felix T. Boylan, New York, N. Y.

Application October 25, 1937, Serial No. 170,898

6 Claims. (Cl. 209—110)

This invention relates to card selecting machines, and more particularly to such a machine adapted to select and segregate unpunched cards from a mass of cards, some of which are punched and some unpunched. The invention is particularly adapted and designed for selecting unpunched cards representing delinquent accounts in establishing such as personal loan departments of banks, personal loan companies, department stores, and installment houses generally which sell merchandise or the like on a partial payment plan. The prime object and purpose of the machine is to effect a saving of time and effort in picking out delinquent accounts, which is now commonly done by hand, at weekly or monthly intervals corresponding to the dates when payments should be made. The invention is designed for use with a card index system wherein as payments are made on a given account the card representing that account is punched at a designated locality thereon, for that particular payment. The foregoing, and other objects and advantages of the invention will be better understood from the following detail description taken in connection with the accompanying drawings, and the distinctive features of novelty will be thereafter pointed out in the appended claims.

Referring to the drawings:

Figure 1 is a plan view of a machine embodying the invention;

Figure 2 is a side view thereof;

Figure 3 is a side view of the side opposite that of Figure 2;

Figure 4 is a lengthwise vertical section approximately on line 4—4 of Figure 1;

Figure 5 is a vertical section on line 5—5 of Figure 1;

Figure 6 is a transverse section on line 6—6 of Figure 4.

Figure 7 is a transverse section on line 7—7 of Figure 3.

Figure 8 is a partial view, partly in elevation and partly in section on a relatively larger scale of the left hand portion of the machine as seen in Figure 1.

Figure 9 is a detail section on line 9—9 of Figure 8.

Figure 10 is a view partly in elevation and partly in vertical section showing the right hand portion of the machine as seen in Figure 1.

Figure 11 is a sectional detail on line 11—11 of Figure 10.

Figure 12 is a view similar to Figure 10 but showing the operative parts in a different position.

Figure 13 is a view also similar to Figure 10 showing the operative parts in still another position.

Figure 14 is a sectional detail on a larger scale on line 14—14 of Figure 6.

Figure 15 is a detail elevation illustrating a presser foot shown in Figure 14, and,

Figure 16 is an elevation of a ledger or index card adapted for use with the invention.

1 indicates a hopper or container for a stack of 10 cards C of the character indicated in Figure 16, these cards having an area C' adapted to be punched at pre-determined points for the successive installment payments as they are made.

2 indicates a pusher finger adapted to push the 15 lowermost card successively from the stack into an engagement with a pair of feed-rollers 3. The pusher-finger 2 is adjustably fixed at the upper end of the bell crank lever 4 fulcrumed to the machine frame at 5 and having an extending 20 arm 4a engaged by a tension spring 6 tending to retract the finger 2. The pusher finger 2 is intermittently pressed forward to eject a card by a cam 7 fixed on a shaft 8 which is the prime drive shaft of the machine, this cam acting upon a roller 9 borne at the end of an adjustable link 10 pivoted at 10a to the lever 4. The lower one of the feed rollers 3 is swingingly mounted on arms 11 fulcrumed to the frame at 12 and acted on by tension springs 13 tending to press such 30 lower roller upward to grip the paper between it and the upper roller which is positively driven. This drive to the upper one of the rollers 3 is effected through a pinion 14 on the shaft thereof which meshes with a gear 15 on the prime drive shaft 8.

16 denotes a spring presser foot mounted just in advance of the rollers 3 and adapted to press upon the card as it is moved out from the stack and cause it to at once stop after it has cleared the rollers 3. For this purpose the presser 35 foot 16 is slideably mounted in a hollow screw 17 adjustably threaded in a block 18 mounted on the frame. The upper part of the hollow screw 17 houses a compression coil spring 19 to yieldingly press the foot 16 downward upon the card just in

advance of the feed rollers 3. The presser foot 16 is preferably in the form of a yoke pivoted as indicated at 16a to the lower end of the stem 16b and thus having spaced apart card engaging areas 16c exerting an equalized pressure upon the card 40 as it is pressed upon the guide rails 16d over which it slides. I provide an adjustable gate adapted

to admit a single card, but only one at a time to be fed outward from the bottom of the card stack. For this purpose I provide a gate bar 20 45

50

55

Figure 12 is a view similar to Figure 10 but showing the operative parts in a different position.

adjustably mounted on the housing block 18 and engaged by a screw 21 fitted in said block to adjust said gate bar with a pre-determined spacing above a fixed lower plate 22. Some distance 5 in advance of the rollers 3 and in the line of card feed, I mount a second pair of rollers, the upper one 23 of which is positively and continuously driven by a shaft 24 and worm gearing 25, 26 from the prime drive shaft. The lower roller 27 10 operating with the roller 23 is mounted on a crank arm 28 fulcrumed to the frame at 29 and having a tension spring 30 engaged therewith tending to move it upward toward the upper roller. One member of the crank arm 28 bears a roller 31 15 engaged by a cam 32 on the main shaft 8, this cam being thus adapted to lower the roller 27 from feeding engagement with the roller 23 at intervals as presently further described. 33 denotes a 20 finder or detector finger operative a short distance in advance from the rollers 23. This finger is adapted to operate through a selected one of the holes 34 of a template 35 mounted on the frame just ahead of the rollers 23. To enable the finger 33 to be adjusted so as to operate 25 through any one of the selective holes 34, it is clamped for endwise adjustment as indicated at 36 at the end of a bell crank lever 37. The lever 37 is mounted for lateral adjustment on a shaft 39, a clamp screw for securing it an adjusted 30 position on said shaft being indicated at 40. The other arm 37a of said bell crank lever bears a roller 41 engaged by a cam 42 fixed on the main shaft 8, so that thereby the finger 33 is lifted and permitted to drop intermittently. 43 indicates 35 a deflector piece mounted for reciprocation just below the line of feed of the cards when they are not deflected by the finger 33. This deflector member has its upper surface 43a parallel with the line of undeflected card feed with a lower 40 surface 43b sloping downward from a pointed extremity 43c, which extremity is at the locality of operation of the finger 33. The deflector 43 is slideably mounted on a bracket 44, the under surface of which slopes downward. For reciprocating 45 the deflector 43 it is engaged by an arm 45 fixed to a rock shaft 46 journaled in the machine frame, the outer end of such shaft having fixed thereon an arm 47 engaged with a link 48. The link 48 is engaged by a tension spring 49 secured 50 to the frame and causing a roller 50 thereon to engage with a cam 51 fixed on main shaft 8. 52 denotes a pair of feed rollers mounted in position to engage the undeflected cards and advance them to a receiver therefor. The lower one of 55 these rollers is mounted on a bell crank lever pivoted at 53 to the frame and spring-pressed upward as indicated at 54 like the other rollers already described. The upper roller 52 is continuously driven by worm gearing 55 from the 60 end of the shaft 24.

It may now be understood that as the cards are successively delivered from the stack C to the first feed rollers 3, they will be fed therethrough, and when cleared of said rollers the punched area 65 C' thereof is located in alignment with the template 35, the presser foot 16 preventing any excess movement of the card. Thereupon the finger 33 is moved downward by cam 32 through the selected one of holes 34 of template 35, the lower feed roller 27 being then depressed to inoperative 70 position by the cam 32. In this movement if the card has been punched so that the finger 33 registers with a punch hole, as seen in Figure 10, the card is not deflected but will be permitted 75 to continue its straight onward movement upon

the ensuing withdrawal of the finger 33. In such case the card passes over the deflector 43 into engagement with the feed rollers 52 under the action of the rollers 23, 27, which become operative as soon as the finger 33 is withdrawn. 5 The punched cards are thus delivered into a receiver 56. When a card is fed underneath the template 35 that is not punched at the point for which the machine is set, the finger 33 will engage the card and press its forward extremity 10 downward as seen in Figure 12. The reciprocation of the deflector 43 is so timed that it is advanced over the deflected forward extremity of the card before the finger 33 is withdrawn and thus upon the ensuing feed movement of the 15 card when the roller 27 moves upward to cooperate with the roller 23, the card is deflected downward as indicated at C' and thus drops into a receiver 57, the deflector 43 being then withdrawn in readiness for another movement. 20

The described machine is thus adapted to assort cards rapidly and accurately, selecting the delinquent or unpunched cards and depositing them in the receiver 57, while the punched cards are collected in the receiver 56. 25

I am aware that the invention may be embodied in other specific forms without departing from the spirit or essential attributes thereof, and I therefore desire the present embodiment to be considered in all respects as illustrative and not 30 restrictive, reference being had to the appended claims rather than to the foregoing description to indicate the scope of the invention. 35

Having now described my invention, what I claim as new and desire to secure by Letters Pat- 35 ent is:

1. A machine of the kind described comprising means for feeding cards successively to a selector station, a reciprocating combined selector and deflector member located at said station and constructed and arranged to engage an advance edge of unpunched cards and deflect them out of the direct line of card feed and cooperative reciprocating means adapted to engage the deflected edge of such cards and direct them to a receiver 40 separate from the receiver for the punched cards. 45

2. A machine as described in claim 1, wherein the cooperative reciprocating means embodies a wedge shaped member mounted to reciprocate in parallelism with the direct line of card feed, 50 and having a sloping lower surface for deflecting the cards.

3. A delinquency card selecting machine comprising means for delivering cards successively from a card stack to a selector station with an 55 advanced portion of the card at said station free to be moved transversely, means for holding the cards momentarily stationary at said station, intermittently operative feeding means for delivering the cards from said station, a detector finger 60 mounted at said selector station for two-direction adjustment and equipped with means for causing it to engage the advance edge of an unpunched card to press upon and deflect it from the direct line of card feed, and means also operative at 65 said selector station for engaging the cards so deflected to guide them to a receiver separate from which receives the punched cards.

4. A machine as described in claim 3 having a template mounted at the selector station at one 70 side only of the line of card feed with a series of holes therein, through which said detector finger is adapted to operate to press upon and deflect unpunched cards according to the setting thereof. 75

5. A delinquency card selecting machine comprising a holder for a stack of cards, means for discharging the cards individually and successively therefrom to a selector station with a forward 5
end portion thereof free to be moved transversely, means for holding each card momentarily stationary at said station, and a combination selector and deflector member operative at said station arranged to press upon unpunched cards representing delinquent accounts to deflect and segregate them from the mass of punched cards for delivery to a receiver separate from the receiver for the punched cards.

6. A delinquency card selecting machine comprising means for delivering cards successively from the card stack to a selector station with a forward portion thereof free to be moved transversely, means for holding each card momentarily 5
stationary at said station, intermittently operating feeding means for delivering the cards from said station, and a detector finger at said selector station mounted and equipped with means for causing it to engage the advance edge of an unpunched card to press upon and deflect it from the direct line of card feed of punched cards. 10

FELIX T. BOYLAN.
